(57) CLAIM

The ornamental design for a “USB storage device,” as shown and described.

DESCRIPTION

FIG. 1 is a perspective view of USB storage device showing our new design;

FIG. 2 is a front view thereof;

FIG. 3 is a rear view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is a perspective view thereof shown in an alternate position.
